UNITED STATES PATENT OFFICE

95,914

DESIGN FOR A FINGER RING

Jack M. H. Le Bolt, Chicago, Ill., assignor to
Lebolt and Company, Chicago, Ill., a corpora-
tion of Delaware

Application March 11, 1935, Serial No. 55,838

Term of patent 7 years

To all whom it may concern:

Be it known that I, Jack M. H. Le Bolt, a citizen of the United States, residing at Chicago, county of Cook, and State of Illinois, have invented a new, original, and ornamental Design for Finger Rings, of which the following is the specification, reference being had to the accompanying drawing, forming part thereof.

In the drawing:—

Fig. 1 is a face view of a finger ring, and
Fig. 2 is a top plan view of Fig. 1.

I claim:—

The ornamental design for a finger ring, as
shown.

JACK M. H. LE BOLT.
